CHARLES NADWORNEY, OF BAYONNE, NEW JERSEY, ASSIGNOR OF TWO-THIRDS TO
LOUIS BORACK, OF BAYONNE, NEW JERSEY.

COIN-CONTROLLED VENDING MACHINE.

Application filed May 5, 1924. Serial No. 711,136.

This invention relates to a coin controlled vending machine.

The object of the invention is the production of a machine, which is particularly adapted to dispensing handkerchiefs when a coin is introduced into its chute, although it may be used for dispensing other objects. A second object is the production of a machine in which the articles dispensed, can not be taken from the machine by an unauthorized person tampering therewith. A third object of the invention is to produce simple means for charging the machine with the objects to be dispensed. A forth object is the production of means, to securely maintain the coins used to operate the dispensing mechanism of the machine in a coin drawer.

The organization of the invention comprises a machine with a coin controlled lever, that discharges the handkerchiefs or other objects dispensed, and which coacts with the movements of a door over an opening through which the handkerchiefs or other objects are discharged.

Fig. 1 represents sections of a coin controlled vending machine exemplifying the invention as on the lines 1, 1, and 1^a, 1^a of Fig. 3; Fig. 2 shows a section on a reduced scale as on the line 2, 2 of Fig. 3; Fig. 3 shows a section of Fig. 1 on the line 3, 3 and Fig. 4 is a section on the line 4, 4 of Fig. 3.

The machine is indicated with a casing comprising the front wall having the upper portion 20, with the opening 21 for the glass 22. The lower portion 23 of the front wall is connected to its upper portion, by the curved connecting portion 24. In the lower end of the portion 23 is formed the outlet opening 25 with the cup shaped receiving platform 26. Openings 27, 28 and 29 are formed in the portion 23. The rear wall of the casing is indicated at 30, and side walls 31 and 32 connect the front wall having the portions 20 and 23 and the rear wall 30. An opening 33 is formed in the wall 31 for the door 34. A lock 35 secures the door 34 in place. An intermediate wall 36 extends the total height of the casing between the front wall having the portions 20 and 23 and the rear wall 30. Openings 39 and 40 are formed in the wall 36.

The wall 36 divides the casing into the chambers A and B.

The bottom of the casing is shown at 41 and the roof at 42.

The chamber A is provided with the platform 43 having the opening 44, which forms with the walls and bottom of the casing, the bottom chamber C. Stop pins 44^a and 44^b extend up from the platform 43.

In the chamber B is indicated the vertical wall 45, which extends a little below the top end of the portion 23 and joins with the walls 31 and 36 to form the charging chamber D for the objects operated upon, in this instance handkerchiefs. An opening is formed in the wall 45 for the glass 46. A horizontal wall 47 has formed therewith the inclined wall 48 which extends to the opening 25 of the portion 23. An outlet opening 49 is formed between the bottom end of the wall 45 and the wall 48. A pair of brackets 50 are fastened to the lower end of the wall 45, and have hinged thereto the door 51, by means of the hinge pin 52. The latter has formed therewith the hook 53.

A pair of guides 55 extend up from the platform 43, and guide the movable cross-head 56 having an opening 57 with the perpendicular rear wall 58 and the front curved wall 59. A push bar 60 extends from the front end of the cross-head 56 through the opening 28 of the portion 23 of the front wall. A bracket 63 is fastened to the cross-head 56 by means of the screws 64. A bracket with the inclined member 66 and the horizontal leg 67 is fastened to and extends from the bracket 63. An opening 68 is formed in the leg 67 and engages the hook 53.

A plate spring 72 has one end fastened to the wall 30 by means of the screw 73 and its other end is fastened to the bracket 63, by means of the screw 74. The said spring tends to move the cross-head 56 toward the portion 23 of the front wall. An inclined chute 75 for the coin 76 used to operate the machine, extends through the opening 27 in the portion 23 of the front wall and has formed therewith the flange 77, which is fastened to the said portion 23.

The chute is of a size to admit a coin of a predetermined size to drop therethrough, and can be replaced by chutes adaptable to coins of different sizes.

A lever is indicated with the rectangular

curved member 78 having the slot 79 extending up from its lower edge, and the angular shaped member 80. A bracket 81 is fastened to the wall 36, and the said lever 5 is hinged thereto at about its central portion by means of the pin 82. A portion of the member 78 is always located opposite the chute 75.

In the chamber C is located the coin drawer 86, with the front wall 87 and the rear wall 88. A plate 89 is fastened to the front wall 87 and has extending therefrom the knob 90. A pair of guides 91 fastened to the bottom 41 of the casing maintains the 15 coin drawer 86 in proper position. A lock 92 is provided for the drawer 86 to lock it in place.

To use the machine the door 34 is opened and a plurality of handkerchiefs 95 are 20 located in the chamber D with the bottom-most one upon the wall 47, after which the door 34 is again locked in position.

To remove a handkerchief the user inserts a coin 76 in the chute 75, and it rolls 25 into the opening 57 of the cross-head 56 and bears between the wall 59 and the member 78 of the lever hinged on the pin 82. The user now pushes the push bar 60 of the 30 cross-head 56 until the latter bears against the stop pin 44^a, and thereby the angular shaped member 80 of said lever swings and pushes the lowermost handkerchief out of the chamber D, which latter then falls through the opening 49 upon the inclined wall 48 and 35 is deposited upon the receiving platform 26 after passing through the opening 25. As the cross-head 56 moves toward the stop pin 44^a, the coaction of the opening 68 in the leg 67 swings the hook 53 and the door 51, to allow the handkerchief to pass through 40 the opening 49.

When the cross-head 56 has been pushed toward the rear side of the casing of the machine and bears against the stop pin 44^a, the 45 slot 79 of the rectangular member 78 of the lever is brought in the path of the coin 76, and the latter then rolls through said slot 79 and drops through the opening 44 into the coin drawer 86. The user then releases the 50 push bar 60 and the spring 72 forces the cross-head 56 to its forward position and to bear against the stop pins 44^b. The other movable elements are at the same time brought to their original position.

The door 51 prevents an unauthorized person withdrawing any of the handkerchiefs or other objects dispensed from the machine, without first inserting a coin in the chute 75.

Various modifications may be made in the invention and the present exemplification is to be taken as illustrative and not limitative thereof.

Having described my invention what I desire to secure by Letters Patent and claim 65 is:

1. In a coin controlled vending machine the combination of a lever hinged therein comprising a pair of members, one of said members having a slot and the second member 70 adapted to dispense an object from the machine, a movable cross-head in the machine adjacent to the member having the slot and adapted to hold a coin between it and said member adjacent thereto, and a 75 flexible medium in the machine tending to maintain the cross-head in its forward position to receive said coin, the member of the lever having the slot moved to bring its slot in line with said coin, when said cross-head is moved to the other end of its stroke.

2. In a coin controlled vending machine the combination of a casing, a chamber in the casing for objects to be discharged therefrom, a door coacting with an outlet opening of said chamber, a lever hinged in the machine comprising a pair of members, one of said members having a slot and the other member 85 adapted to discharge the said objects through the outlet opening of said chamber, a movable cross-head in the machine below said member having the slot and adapted to hold a coin between it and said member, means tending to locate the cross-head in its forward position to receive said coin, the member of the lever having the slot moved to bring the slot in line with said coin and the said door located in its open position when said cross-head is moved to the other end of its stroke.

3. In a coin controlled vending machine the combination of a casing, a chamber in the casing for objects to be discharged therefrom, a hinge pin with a hook at one end hinged over an outlet opening at the lower end of said chamber, a door extending from said hinge pin coacting with said opening, a cross-head adapted to reciprocate in the machine and having an opening in the body thereof and a push bar at one end extending outside of the casing, a platform with an opening in said machine supporting said cross-head, a lever hinged in the machine with one member thereof extending into the lower end of said chamber and having a curved member with a slot extending over said cross-head, a bracket having an opening extending from said cross-head, said opening engaging the hook of said hinge pin and means to insert a coin between a wall of the opening of said cross-head and the curved member of said lever.

Signed at Bayonne, in the county of Hudson and State of New Jersey, this 25th day of April, A. D. 1924.

CHARLES NADWORNEY.
